UNITED STATES PATENT OFFICE

GEORGE T. SMILEY AND WALTER R. OHSE, OF HOUSTON, TEXAS

REFRIGERATING UNIT

Application filed October 22, 1928. Serial No. 314,179.

The present invention relates to refrigerating units and more particularly to devices of this character employing the use of a plurality of superposed flues having a refrigerating coil associated therewith and through the action thereof to cause a circulation of the air within the compartment within which the unit is mounted whereby to subject the air to the cooling action of said coils.

10 An important object of the invention is to provide a refrigerating unit of this character adapted for use for general household purposes as well as for cooling relatively large enclosed areas, such as theatres and the like, packing plants and other public and commercial places.

15 A still further object is to provide a refrigerating unit of this character of an efficient and practical construction which is inexpensive to manufacture and maintain in operation and otherwise well adapted to the purposes for which the same is intended.

20 Other objects and advantages reside in the special construction, combination and arrangement of the various elements forming the invention as more fully hereinafter described and claimed, reference being had to the accompanying drawings forming part hereof, wherein like numerals refer to like 25 parts throughout, and in which:

Figure 1 is a vertical sectional view through a refrigerating compartment showing one of the units constructed in accordance with my invention in end elevation and 30 mounted in position therein,

Figure 2 is a vertical longitudinal sectional view through the unit.

Figure 3 is an end elevational view of one 35 of the supporting legs for the unit, with parts broken away and shown in section,

Figure 4 is a transverse sectional view through one of said supporting legs,

Figure 5 is a bottom plan view of one of 40 the plate and coil sections provided for forming the flues of the unit,

Figure 6 is a perspective view of a modified type of unit formed of a series of spaced apart shallow brine tanks having the refrigerating coil arranged in each of said tanks,

45 Figure 7 is a similar view of a further mod-

ified form of the invention dispensing with the use of the supporting legs and formed with the flue plates and coils cast integrally, and

50 Figure 8 is a perspective view of one of the supporting brackets for the outer edges of the flue plates used with the form of invention illustrated in Figures 1 and 2 of the drawing.

55 Referring now to the drawing in detail, the invention comprises a refrigerating unit for cooling rooms or compartments, of any size or shape, for the purpose of illustration such room or compartment being indicated generally at 5.

60 A refrigerating unit is preferably supported in the upper portion of said room or compartment and comprises a refrigerant feed boiler composed of a pair of vertically arranged spaced parallel legs 6 of hollow 65 formation and connected at their upper ends by a horizontally disposed head 7. The head 7 is likewise of a hollow formation so as to permit the free circulation of the refrigerant contained in the legs and the head throughout the entire interior portion thereof.

70 At one end of the head 7 is formed an intake port 8 and at one side of the head is also formed a hollow boss 9 constituting a 75 discharge port for the head and with which is attached a discharge pipe 10 for returning the refrigerant to the compressor unit (not shown) of a type generally employed in an apparatus of this character. Suitable 80 automatic control valves (not shown) of a type well known in the art may be fitted in the intake and discharge parts to regulate the admission and discharge of the refrigerant into and out of the boiler.

85 The boiler may be suspended from the ceiling 11 of the room or compartment by means of hangers or straps 12. Openings 13 are arranged at vertically spaced intervals in each of the legs 6 within which the ends of coiled pipes 14 are fitted, the opposite ends 90 of said pipe communicating with the respective legs.

95 Each side of the legs may be provided with a series of the coil pipe 14, as clearly illustrated in Figure 1 of the drawing, or if de-

sired the pipe may depend from only one side thereof.

The coil pipes 14 and their sections immediately adjacent the legs extended outwardly therefrom and provide supports for a series of flue plates 15 arranged on the upper edges of said coil pipes and disposed in parallel relation with respect to each other whereby to form flues between a pair of said plates.

10 The outer ends of the pipes 14 and plates 15 are inclined upwardly and are supported by brackets 16 extending vertically along the outer edge of the plate and inwardly above the uppermost of said plates for attachment 15 at their upper ends to the strap or hanger 12.

At spaced intervals in the length of the bracket 16 are formed offset portions 17 forming grooves at their inner faces for receiving the outer edges of the plate 15 and thus 20 provide a positive means of keeping the plates for retaining the outer ends thereof in uniformly spaced relation with respect to each other.

25 The intermediate portion of the coil pipes 14 may be bent angularly as shown at 18 on a horizontal plane with respect to the plate 15, or may be twisted or turned in any desired manner to increase the circulating area of 30 the fluid passing through said pipe.

35 An efficient and practical manner of arranging the coil pipe 14 is illustrated in Figure 5 of the drawing. It is to be understood that the pipes 14 and plates 15 may be constructed separately and assembled in any desired manner upon the units, or may be cast with each other as a unit as illustrated in Figure 7 of the drawing, or if desired the pipes or coils may be cast within a shallow 40 tank of a type indicated at 19 in Figure 6 of the drawing.

When the flues are formed from a series 45 of spaced tanks as illustrated in Figure 6 of the drawing, the ends of the pipe 14 extend through one of the walls of the tank for attachment to the openings 13 of the boiler leg and either the tank may be filled with a refrigerating agent, such as brine or the like. For this purpose filler caps 20 are provided 50 for each of the tanks.

The inner ends of the tank may be soldered or secured in any desired manner to the sides of the legs 6 so that the same will be rigidly attached in position thereto. Although the 55 tanks 19 are shown as extending at right angles to the supporting legs, it is to be understood that the same may, if desired, be inclined upwardly and outwardly in the same manner as the plates 15.

60 In the form of the invention illustrated in Figure 7 of the drawing, the boiler composed of the legs 6 and head 7 may be dispensed with and the connection 21 provided for attaching the coil to the refrigerant de- 65 vice.

In this form of the invention it is desirable to attach an expansion valve 22 to the connection 21. Furthermore in this form of the invention the plates 15 and associated coils 14 are shown as being cast integrally, 70 the plates 15 are supported in spaced parallel relation by slip joints 23 disposed at each corner of the plates and having connection through the plate with the adjacent coil 14 so as to connect the refrigerant conduits in 75 series.

Through the use of the slip joint 23 a free circulation of the fluid throughout each coil of the entire unit is provided. An outlet pipe 24 is attached to the lowermost coil 14, 80 preferably at the corner of the unit opposite from the intake connection 21.

85 The unit as illustrated in Figure 7 of the drawings may be suspended or supported in any desired manner within the room or compartment with one edge thereof in an upwardly inclined position for the purpose of facilitating the circulation of the air through the flues formed by the plates and coils.

90 It is obvious that our invention is susceptible to various changes and modifications in construction without departing from the spirit of the invention or the scope of the appended claims, and we accordingly claim all such forms of the device to which we are 95 entitled.

Having thus described our invention, what we claim as new is:

1. A refrigerating unit comprising a hollow inverted U-shaped element having intake and discharge ports and a plurality of vertically spaced refrigerant conduits communicating at their opposite ends with the respective legs of the inverted U-shaped elements.

100 2. A refrigerating unit comprising a hollow inverted U-shaped element having intake and discharge ports, a plurality of vertically spaced refrigerant conduits having their opposite ends communicating with the respective legs of the said inverted U-shaped elements, and baffles associated with said refrigerant conduit, and relatively spaced to define flue passages between adjacent baffles.

110 3. A refrigerating unit comprising a hollow inverted U-shaped element having intake and discharge ports, a series of refrigerant conduits extending laterally from the respective opposite sides of the legs of the inverted U-shaped elements, each of said conduits having its opposite ends communicating with the respective legs and being vertically spaced relative to adjacent conduits, baffles associated with the said refrigerant conduits, and in relatively spaced relation to define flue passages between the conduits, said baffles and said conduits being inclined relative to the supporting legs.

115 4. A refrigerant unit comprising a hollow inverted U-shaped element having intake and 120 discharge ports, a plurality of vertically spaced refrigerant conduits having their opposite ends communicating with the respective legs of the inverted U-shaped element, and baffles associated with said refrigerant conduits, and in relatively spaced relation to define flue passages between the conduits, said baffles and said conduits being inclined relative to the supporting legs.

125 5. A refrigerant unit comprising a hollow inverted U-shaped element having intake and 130 discharge ports, a plurality of vertically spaced refrigerant conduits having their opposite ends communicating with the respective legs of the inverted U-shaped element, and baffles associated with said refrigerant conduits, and in relatively spaced relation to define flue passages between the conduits, said baffles and said conduits being inclined relative to the supporting legs.

discharge ports, a plurality of circulating coils extending outwardly from one side of the legs of the said inverted U-shaped element, said coils being spaced vertically throughout the length of the legs and having their respective opposite pins in communication with the respective legs, and baffles associated with each coil for defining flue passages between the coils, each of said baffles being of hollow construction to provide a brine receiving tank.

In testimony whereof we affix our signatures.

GEORGE T. SMILEY.
WALTER R. OHSE.
